UNITED STATES PATENT OFFICE.

OLLIE C. GEORGE, OF CRYSTAL LAKE, ILLINOIS.

DESIGN FOR A FENCE.

Application filed July 10, 1924. Serial No. 10,121. Term of patent 7 years.

To all whom it may concern:

Be it known that I, OLLIE C. GEORGE, a citizen of the United States, residing at Crystal Lake, in the county of McHenry and State of Illinois, have invented a new, original, and ornamental Design for a Fence, of which the following is a specification, reference being had to the accompanying drawing, forming part thereof.

The figure is a perspective view of a fence, showing my new design.

I claim:—

The ornamental design for a fence, as shown.

OLLIE C. GEORGE.
